UNDERGARMENT

William Murphey, Chattanooga, Tenn.

Application August 4, 1945, Serial No. 608,994

1 Claim. (Cl. 2—80)

1

The object of my invention is to provide a new and useful garment, particularly for children, which has certain improvements over what is disclosed in my Patent No. 2,106,646.

It is a special object of my invention to provide a novel seat opening and flap, a novel insert in the crotch-portion of the garment, novel moccasins woven as a part of the garment and means whereby the length of the leg may be readily lengthened.

I attain these and other objects of my invention by the means illustrated in the accompanying drawing, in which—

Fig. 1 is a detailed view of a portion of the leg and foot of the garment, partly in side elevation and partly in vertical section;

Fig. 2 is a perspective rear view of the garment as worn by a child;

Fig. 3 is a transverse section through the foot-portion of the garment.

Like numerals designate like parts in each of the several views.

The leg terminates in the foot-portion 14, to which the sole 16 is stitched, along the line 15.

2

The sole is shaped at the front by the single line of stitching 17, as shown in Figs. 3 and 6, and at the rear by the line of stitching 18, as shown in Fig. 3.

5 What I claim is:

In a garment of the type described terminating in foot-portions, sole strips stitched to the foot-portions, the sole strips having centrally disposed seams at the toe and heel to shape the garment 10 to the foot.

WILLIAM MURPHEY.
